CYCLE SADDLE SEAT

Martin J. Bird, Norwalk, Ohio, assignor to The Faulhaber Company, Monroeville, Ohio, a corporation of Ohio

Filed Sept. 10, 1964, Ser. No. 81,676

Term of patent 14 years

(Cl. D90—16)

FIG. 1

FIG. 2

FIG. 3

FIG. 1 is a view in side elevation of a cycle saddle seat showing my new design;

FIG. 2 is a top plan view thereof, and

FIG. 3 is a view in front elevation looking in the direction of arrow 3 in FIG. 1.

I claim:

The ornamental design for a cycle saddle seat, as shown.
